UNITED STATES PATENT OFFICE.

WILLIAM R. MORSE, OF CHICAGO, ILLINOIS.

MARKING DEVICE.

SPECIFICATION forming part of Letters Patent No. 686,692, dated November 12, 1901.

Application filed January 3, 1899. Renewed April 18, 1901. Serial No. 56,406. (No model.)

To all whom it may concern:

Be it known that I, WILLIAM R. MORSE, a citizen of the United States, residing at Chicago, in the county of Cook and State of Illinois, have invented a certain new and useful Improvement in Marking Devices, of which the following is a specification.

My invention relates to marking devices, and has for its object to provide a new and improved marking device particularly adapted for marking wearing-apparel in laundries and the like, so that the apparel of different customers will not become confused.

My invention is illustrated in the accompanying drawings, wherein—

Figure 1 is a plan view, with parts omitted, of a device embodying my invention. Fig. 2 is a section on line 2 2, Fig. 1. Fig. 3 is a section through the supporting device for the article to be marked. Fig. 4 is a longitudinal section with parts omitted on line 4 4, Fig. 1. Fig. 5 is a section on line 5 5, Fig. 4. Fig. 6 is a view of the tool used to control the marking-bars. Fig. 7 is a cross-section through one of the marking-bars. Fig. 8 is a view showing the foot-treadle for moving the part upon which the article to be marked is placed.

Like letters refer to like parts throughout the several figures.

In operating laundries it is necessary to provide some means for marking the articles of different people, so that they can be returned to their owners after being passed through the laundry. Heretofore it has been customary to mark these articles by hand with indelible ink. This hand-marking was made necessary by the conditions to be met; and the object of my invention is to provide a machine capable of overcoming the difficulties attending such marking and which will obviate the necessity of marking by hand.

I have illustrated one form of my device in the accompanying drawings in a simple and diagrammatic manner with a view of making my invention clear; but it is of course evident that the form, construction, and arrangement of the several parts herein shown may be varied and that parts may be omitted and others used in connection with parts not herein shown without departing from the spirit of

my invention. I therefore do not limit myself to the construction shown.

Referring now to the accompanying drawings, I have shown a series of marking-bars A, 55 suitably mounted, so that they may be moved in and out, the bars being provided with any desired marking characters A' A'. It is of course evident that these characters may be the letters of the alphabet, figures, or of any other 60 suitable description, and I do not limit myself to any particular characters. For the purpose of illustration I have shown the marking-bars as provided with the letters of the alphabet in consecutive order. These bars are mounted 65 in any desired manner and are adapted to be moved back and forth, so that any one of the characters may be moved opposite the article to be marked. As herein shown, these bars rest upon the supporting device B, mounted 70 upon a suitable table D, and are confined laterally by the side pieces B'. I prefer to separate the several bars by the thin stationary pieces B², so that the several bars will be independent of each other. When the supporting device B is used, it is cut away, as shown, for example, at B³, Fig. 4, so that the characters on the several bars may be exposed through this opening or cut-away place. Opposite this opening B³ is the opposed surface 75 C, upon which the article to be marked is placed. The characters on the marking-bars and the opposed surface C are adapted to be moved relatively, so that the article to be marked and the characters may be brought 80 into contact with each other. Any suitable means for this purpose may be employed. As herein shown, the opposed surface C is connected with a movable part C', mounted 85 on a suitable guide associated with the table 90 D, and is adapted to be moved upwardly toward the characters on the marking-bars. This movement may be obtained in any desired manner—as, for example, by means of an ordinary lever C² and foot-treadle. (See 95 Fig. 8.) The opposed surface C is preferably made of some material adapted to give, so as to compensate for the inequalities or unevenness of the surface of the material to be marked. I prefer to form this opposed surface 100 of soft rubber or the like. As illustrated in Fig. 3, the soft rubber C rests upon the

part C³, and a suitable adjusting device is provided, so that the opposed surface C may be adjusted to be substantially parallel with the faces of the characters on the marking-bars. As herein shown, this adjustment is obtained by means of the thumb-screw C⁴. A suitable inking device is provided, so that the characters when they are brought opposite the opening B³ may be inked before they are brought into contact with the article to be marked. This inking may of course be done in any desired manner, and I have shown a simple construction for this purpose.

Referring now to Fig. 4, I provide an ink-reservoir E, adapted to be moved under the opening B³, so as to be brought into contact with the characters exposed through said opening and to be moved up in contact with said characters. This reservoir, as shown, is mounted upon suitable guideways E' by means of the wheels E² and is provided at its front end with the rollers E³ E⁴, about which is passed the endless belt E⁵. This endless belt is made of material adapted to become saturated with the ink, such as cloth or the like, and the roller E³ is so positioned that it projects slightly above the upper face of the opening in the ink-reservoir. This permits the endless belt to be brought into contact with the characters on the marking-bars. I prefer to provide a suitable adjusting device E¹⁰ for adjusting the face of the roller E³, so that it will be parallel with the faces of the characters on the marking-bars, thus insuring the inking of all of said characters. I have found that ordinarily the ink will be drawn up by capillary attraction, so as to saturate the face of the belt opposed to the characters. In order to insure a sufficient inking of the characters, I provide the roller E³ with a gear E⁶, adapted to engage a short rack E⁷ during its movement toward the characters. It will be seen that this engagement between the gear and the rack rotates the rollers and moves the endless belt, so that the part which was submerged below the ink will be brought to the top of the roller, and thus be opposed to the characters. The inking device is moved forward in any desired manner. As herein illustrated, a bell-crank lever F is connected with the inking device and the table D. This bell-crank lever is provided with a suitable foot-treadle F' and a retracting-spring F². By pressing on the treadle it will be seen that the inking device will be moved forward and will be retracted by the spring F² when the pressure on the treadle is removed. In view of the peculiar conditions to be met in marking articles for laundries I have found it necessary to use a thin ink. This ink evaporates very rapidly, and to prevent this I provide a means for closing the opening in the reservoir E by bringing said opening against an opposed lid or cover E⁸, connected with the under side of the supporting device for the marking-bars. The edge of the opening in the ink-reservoir or the opposed face

of the cover E⁸ is preferably provided with a suitable layer E⁹ of some soft material which makes a tight joint. In order to insure the closing of the opening in the ink-reservoir, I provide each of the guides E' with a suitable block G, having an inclined face, as shown. These blocks are so situated that when the ink-reservoir is withdrawn from beneath the opening B³ the front set of wheels E², which pass along these guides, engage the inclined faces of the blocks G and move the opening in the ink-reservoir against the cover or lid E⁸, as shown in full lines in Fig. 4. These blocks are so located that the rear set of wheels E² strike them when the roller E³ is opposite the opening B³, and hence the forward movement of the ink-reservoir is limited. The continued pressure on the foot-treadle, however, tilts the ink-reservoir so as to bring the inking-surface in contact with the characters, as shown in dotted lines, Fig. 4. The marking-bars A are provided with a suitable holding device, so that they may be held in any desired position while the marking is being done. I prefer to have this holding device so constructed that the bars may be held with any desired character opposite the opening B³, and I further prefer to have the construction such that the holding device will not prevent the reciprocation of the bars necessary in bringing different characters opposite the opening B³. It is of course evident that any desired construction for this purpose may be used. As herein shown, I provide a series of pins H, located in any suitable position, preferably opposite the opening B³ and mounted in a holding device H'. These pins are preferably provided with springs H², which normally press them toward the marking-bars and are beveled in any desired manner at the ends, so as to fit into the indentations H³ on the top of the bars. When this construction is used, the bars may be moved back and forward, the pins H moving in and out of the depressions H³. These depressions are located so that when a pin H falls within one of them on any given bar a character will be opposite the opening B³. I prefer to provide the end of each bar with a pin I, which engages the stop L² when the bars are in their initial position. This stop L² may be of any construction and may be located in any desired position, such position depending upon the construction of the machine. When said bars are in this position, none of the characters are opposite the opening B³. If now it is desired to move a given character opposite the opening B³, the pin I is grasped and the bar moved outwardly until the desired character is in the desired position. I prefer to provide a tool J, which is provided at its end with a hole, so that it engages the pins I. In order to facilitate the operation of the device, I prefer to place on the tops of the marking-bars the same characters that are placed beneath them, the two sets of characters being so positioned with relation to each other that when the

marking character on the bottom of the bar is opposite the opening B³ the same character on top of the bar is just in front of the edge of the holding device H'. (See Fig. 1.) When 5 this arrangement is used, the operator will know that the marking characters are in the proper position if the bars are moved so that the same characters are in line in front of the holding device H'. Another means of indicating 10 when the proper marking character is opposite the opening B³ is obtained by placing the characters on a stationary piece at one side of the marking-bars—for example, the piece or pieces B'. This is illustrated in Fig. 15. The characters in this event are properly spaced and are placed upon a stationary piece in the reverse order. If now the end of the bar is drawn out to be opposite a given letter on this stationary scale, the same letter on 20 the under side of the bar will be opposite the opening B³. It is of course evident that other means for this purpose may be provided. In order to facilitate the movement of the marking-bars back and forth, I may place at each 25 end thereof a friction-wheel A⁵, said friction-wheel bearing upon the face of the supporting-piece B. The marking-bars may be of any desired shape and construction and the characters may be attached thereto or formed 30 thereon in any desired manner. I have shown in the drawings a construction wherein the characters are formed on a strip A⁶ of comparatively hard rubber. A strip A⁷ of soft rubber is preferably interposed between the 35 characters and the bar, so that the characters may give when the article to be marked is pressed against them, and thus compensate for inequalities in the material to be marked. When this construction is omitted, the same 40 result may be obtained by providing a suitable cushion for the opposed surface C, upon which the article to be marked is supported. This rubber strip may be vulcanized to the marking-bars or may be attached thereto in any 45 desired manner. The characters, whether formed of rubber or otherwise, are preferably shaped so that the part which comes in contact with the material to be marked is comparatively thin, so as to form a sharp clean- 50 cut engaging edge. This is shown in Fig. 7. When this construction is used, the ink runs down to this sharp engaging edge and hangs there until the material is brought into contact with the character. The ink thus sus- 55 pended soaks instantly into the cloth or other material to be marked, and a permanent clean-cut character is produced, which when made with indelible ink is not erased by the process of washing or by otherwise treating 60 the material. Mounted upon the side pieces B' is a sliding piece L, provided with a suitable handle L'. This sliding piece is normally at the outer end of the pieces B'. A suitable weight L³ is preferably connected 65 with the sliding piece L, so as to normally hold it at the end of the side pieces B'. When, for example, the device is being used and a

number of bars are drawn out different lengths, they may all be simultaneously returned to their initial position by moving the 70 sliding piece L forward. During this movement the sliding piece engages the ends of the bars or the pins I and moves them all up against the stop L².

The use and operation of my invention are 75 as follows: When the device is ready for use, the ink-reservoir is provided with sufficient ink and the several marking-bars are preferably in their initial position—that is, with the pins I in contact with the stop L². If now 80 it is desired to mark pieces of wearing-apparel—as, for example, the articles contained in the bundle of a customer—the bars are pulled outwardly until the characters to be placed on the articles are in their proper position opposite the opening B³. The foot-treadle F is then pressed, so as to move the inking device and bring it in contact with the series of characters exposed through said opening. The foot-treadle is then released, 90 and the spring F² moves the inking device back to its initial position. The article to be marked is then placed upon the opposed surface C, and said opposed surface is moved upwardly by means of the foot-treadle associated therewith, so as to bring the article in contact with the characters on the marking-bars. The ink is then taken into the goods and forms the desired characters thereon. The opposed surface is then lowered and the 95 article removed. The several articles upon which similar marks are to be placed are then marked, as above described, and the bars are then moved, so as to change the characters for the articles of the next customer. 105

I have found in practice that the device herein shown will satisfactorily mark not only fine linen, but heavy rough material, and that this device may be used to mark all wearing-apparel ordinarily sent to laundries. 110

I claim—

1. A marking device for laundries, comprising a table, a series of horizontal movable pieces substantially parallel with the face of said table, each of said pieces containing a 115 series of characters, a movable part connected with said table and adapted to support the article to be marked, means for moving said movable part when the article is in position, so as to move said article against the characters on said pieces. 120

2. A marking device, comprising a series of pieces relatively movable and provided each with a series of characters which face downward when in an operative position, said characters being beveled so as to have a sharp engaging face, an inking device for applying liquid ink to said characters when in their operative position, the ink being suspended thereon, an opposed surface upon which the 125 article to be marked is placed, and means for bringing the article and the characters into contact while the contact face of the article is in a substantially horizontal plane, so that 130

the liquid ink is drawn into the substance of the article by the force of gravity.

3. A marking device for wearing-apparel, comprising a series of movable pieces, each 5 having a series of characters thereon facing downward when in their operative position, said characters formed with a sharp engaging face, and means for applying liquid ink to said characters so that it will be suspended 10 on said sharp engaging face.

4. A device for marking wearing-apparel, comprising a series of movable pieces, each provided with a series of characters, said pieces adapted to be moved so that any of 15 the characters may be brought opposite an opposed surface upon which the article to be marked is supported, an inking device for inking said characters when opposite said opposed surface, said inking device comprising 20 a reservoir containing liquid ink, means for moving said reservoir opposite said characters when they are in their operative position, and a device adapted to be saturated with ink contained within said reservoir, said device 25 adapted to make contact with the characters so as to ink them.

5. A device for marking wearing-apparel, comprising a series of pieces, each containing 30 a series of marking characters, an opposed surface upon which the article to be marked is placed, said pieces adapted to be moved so that any desired character may be brought 35 opposite said opposed surface, an inking device for inking said characters when in their operative position, said inking device comprising a reservoir adapted to contain liquid 40 ink, two rollers in said reservoir, one projecting slightly above the mouth thereof, and a belt of material adapted to be saturated with 45 the ink passing around said rollers, and means for moving said reservoir so that said belt is brought into contact with said characters.

6. A device for marking wearing-apparel, comprising a series of pieces, each containing 45 a series of marking characters, an opposed surface upon which the article to be marked is placed, said pieces adapted to be moved so that any desired character may be brought 50 opposite said opposed surface, an inking device for inking said characters when in their operative position, said inking device comprising a reservoir adapted to contain liquid

ink, two rollers in said reservoir, one projecting slightly above the mouth thereof, and a belt of material adapted to be saturated with 55 the ink passing around said rollers, means for moving said reservoir so that said belt is brought into contact with said characters, and a lid for said reservoir adapted to normally cover the same so as to reduce the evaporation of the ink. 60

7. A marking device for laundries, comprising a table, a series of independent pieces mounted in proximity to the face of said table, so as to be separated therefrom by an intervening space, said pieces each provided with a series of characters, a support or partition between the table and said independent pieces, an opening in said partition through which the characters can be successively exposed, a movable part on said table adapted to support the article to be marked, an inking device adapted to be moved so as to ink the characters exposed through the opening in said partition, and means for moving said 75 support so as to bring the article thereon in contact with the exposed characters. 70

8. A marking device for wearing-apparel, comprising a series of movable pieces having 80 characters thereon, so that they may be arranged with reference to each other to produce any desired group of characters; said characters facing downward when in their operative position, and an inking device for applying liquid ink, and adapted for that purpose to move across the face of the characters, 85 a platen opposed to the characters and a suitable frame for supporting the several parts.

9. A marking device for wearing-apparel comprising a suitable supporting-frame, a 90 lower vertically-movable platen, a series of movable pieces provided with characters so that any desired group of characters can be arranged, said characters adapted when in their operative position to face downward toward the platen, a means for applying liquid 95 ink, said inking apparatus adapted to cross the face of the characters between them and the platen.
